SOAP BAR

George Valian, 2701 Bellefontaine, Houston, Tex. 77025

Filed Oct. 26, 1966, Ser. No. 4,467

Term of patent 14 years

(Cl. D73—1)

FIGURE 1 is a top plan view of a soap bar constructed in accordance with this invention.

FIGURE 2 is an end view of the bar shown in FIGURE 1, taken in the direction of the arrow 2 in FIGURE 1.

FIGURE 3 is an end view of the bar taken in the direction of the arrow 3 in FIGURE 1.

FIGURE 4 is a side view of the bar, taken in the direction of the arrow 4 in FIGURE 1.

FIGURE 5 is a side view of the bar taken in the direction of the arrow 5 in FIGURE 1.

FIGURE 6 is a plan view of the bar, with the bar up-side-down in comparison with its FIGURE 1 position.

FIGURE 7 is an end view of the bar, taken in the direction of the arrow 7 in FIGURE 6.

FIGURE 8 is an end view of the bar taken in the direction of the arrow 8 in FIGURE 6.

FIGURE 9 is a side view of the bar, taken in the direction of the arrow 9 in FIGURE 6.

FIGURE 10 is a side view of the bar taken in the direction of the arrow 10 in FIGURE 6.

I claim:

The ornamental design for a soap bar, as shown.
